UNITED STATES PATENT OFFICE

HENRY C. KIRK, OF BALTIMORE, MARYLAND, ASSIGNOR TO SAMUEL KIRK AND SON INCORPORATED, OF BALTIMORE, MARYLAND, A CORPORATION

DESIGN FOR A CANDLESTICK

Application filed May 8, 1928. Serial No. 26,604. Term of patent 14 years.

To all whom it may concern:

Be it known that I, HENRY C. KIRK, a citizen of the United States, residing at Baltimore, in the county of Baltimore and State of Maryland, have invented a new, original, and ornamental Design for a Candlestick, of which the following is a specification, reference being had to the accompanying drawing, forming part thereof.

In the drawing, Figure 1 is an elevational view of a candlestick, showing my new design; and Figure 2 is a section taken on line 2—2 of Figure 1, looking in the direction of the arrows there shown.

I claim:

The ornamental design for a candlestick, as shown.

HENRY C. KIRK.
